GINIA, A CORPORATION OF VIRGINIA.

PROCESS OF TREATING WARP IN LONG CHAIN OR ROPE FORM.

Application filed November 20, 1924. Serial No. 751,054.

To all whom it may concern:

Be it known that we, HAROLD MASON CHASE and GEORGE WILMOT ROBERTSON, citizens of the United States, residing at 5 Danville, in the county of Pittsylvania and State of Virginia, have invented certain new and useful Improvements in Processes of Treating Warp in Long Chain or Rope Form, of which the following is a specification.

Our process is designed for the continuous treatment of long chain warps whereby the white warps are by successive and continuous steps boiled out, cooled, dipped in dye liquid, oxidized, cleaned, dried, and delivered complete ready for the beaming machine without being handled manually.

The illustration is a diagram of the apparatus shown in our Patent No. 1500298 of 20 July 8, 1924, which is adapted to carry out our process.

A long chain warp may be defined as a number of cotton or yarn threads all lying parallel and arranged in rope form consisting of approximately four hundred threads 25 on the average and varying in length from one to twelve thousand yards.

These long chain warps when made are, of course, white and the problem is to dye 30 them a uniform shade and deliver them in a dyed condition for the next step in using the warp with the least labor and expense.

It will be remembered that the threads or ends are not manufactured into the form 35 of a long chain warp except for the purpose of dyeing, bleaching or other chemical treatment; that is to say, it is entirely possible, and is used by some mills, to make white cloth by running the white threads 40 directly from the spools to the beamer, and it is also possible to make colored cloth by dyeing the cotton before it is spun.

In the process we are considering, however, the raw unbleached cotton is spun and 45 formed into the long chain warps. The problem is to dye these long chain warps with indigo, although the process is equally as valuable for other vat dyes.

Prior to our invention of this process, 50 this dyeing of long chain warps was handled in the following way: A long chain warp was brought to a vat equipped with squeeze rollers which in principle was

the same as an ordinary clothes wringer and tub. This warp was passed through the vat containing hot water and some washing material for the purpose of cleaning or wetting the warp, thence through the squeeze rollers into a box or "can." (2) It was manually taken out of this box by the end that went into the box last and passed through the cold water tank for the purpose of cooling it, and again deposited in the box or "can." (3) It was manually taken out of this box and passed through a vat containing reduced indigo. It was then taken out of this indigo vat, passed through the air for some distance to oxidize it, and if a very light shade was wanted, it was then moved to and passed through a washing vat 70 for the purpose of removing any surplus dye and other chemicals. It was then taken to a drier and the process was complete. Now it will be noted that each one of the successive steps above outlined was, so to speak, an independent process; that is to say, in each case the warp was passed through a vat, deposited in a box and taken out of that box again for the next machine by the end that went in last. This, of course, required manual handling and in a great many cases the warp was moved from one part of the mill to another as the successive machines were in separate units some distance apart.

The labor required is, of course, obvious. The result also was that frequently the warp became tangled and the threads were injured in removing them from the various boxes. As the warp was reversed upon each separate step, the fibers were not laid or maintained in the same direction, thereby reducing the strength of the threads themselves, and rendering them more difficult of handling in the beaming process.

In latter years efforts were made to combine the successive steps of this process as much as possible, so as to prevent the loss in labor in handling the warp. This was particularly true because where a deep shade of dye was required, the warp had to be dipped in successive vats or dipped repeatedly in the same vat, so that the warp would take up sufficient dye to give it the necessary shade.

It may be here stated that many years

ago the warp was handled when a deep shade was required through successive vats and the ends were reversed for the reason that the end that went into the dye first took 5 on a deeper shade than the end that went in last. Many years ago a process was worked out to supply to the same vat continuously the necessary dye stuff so that the shade of the warp would be the same from end to 10 end. Up to the time of our Patents, 1500298 and 1500299, if it were necessary to dip the warp into the dyeing vat more than once, this was accomplished by dipping it into the required number of successive vats. 15 By our process we are enabled to carry all of its steps in one machine and use only one dye vat for the number of successive dips necessary to obtain the desired shade. Our Patent No. 1500298 discloses a machine 20 which is adapted to carry out our process by which a warp is taken, boiled out, cooled, dipped in vat dye liquid, oxidized, cleaned dried and delivered completed at the other end ready for the beamer. This is one continuous run. The warp is fed in at one end and delivered at the other. It travels always in the same direction. The fibers of the 25 yarn are all laid and maintained in the same direction and it is, of course, apparent that 30 by our process we are enabled to save considerable labor.

As disclosed in our prior patents just above designated we may, if desired, use agitators in the dye liquid.

35 Of course it is obvious that the warp being treated under our process may be redipped in the dye as many times as may be found necessary to obtain the required shade, the oxidizing step following after 40 each dipping of the warp in the dye.

If a warp is run through a succession of 45 separate noncommunicating tanks, the shade represents the combination of the separate tanks. Bear in mind now, that in a continuous process the warp is not reversed and run in one end first, and then the other, but that the theory is that sufficient dye stuff is supplied continuously to maintain the dye stuff at the required strength. It has been 50 found that by the continuous process where the dye stuff is fed into the tanks it is very necessary that the dye stuff in the successive tanks be maintained at uniform strength to prevent variation in shade. Emphasis is 55 laid upon the fact that in the continuous process there is no opportunity to stop and examine the shade to see whether it is in accordance with the requirement. In the 60 continuous process using a succession of 65 separate tanks, it has been found most difficult to maintain liquid in the successive tanks in the same standard strength for the reason that it is impossible to tell how much dye stuff the warp took out of each particular tank, and if, therefore, it was fed

into the tanks at a continuous rate the strength in the various tanks would vary, and although the same amount of dye stuff might have been fed into the succession of tanks during the process, due to the variation in the strength in the particular tanks, the shade would not be uniform. This applies not only to the chain warp in question, if a long one, but to the successive warps, if 70 passed through the tanks. 75

Therefore, the use of a single tank and the successive dips of the warp into the same tank permits the dye stuff to remain the same strength for each successive dip.

The term single tank as herein used includes one individual tank or a succession of tanks having communication with each other whereby the same body of liquid dye may freely circulate from one tank to the other thus insuring the same standard 85 strength of dye in all tanks or vats. 80

The reference numeral 13 designates a track upon which a truck 12 is adapted to travel. Balls of long chain warps 10 are mounted on said truck. The long chain 90 warp in the single continuous run passes through the boiling out machine or vat 11, thence between squeeze rollers 11^a, thence over a guide roller 11^b and thence into cooling tank 14, thence between squeeze rollers 11^c, thence over a guide roller 11^d, thence 95 into the dye vat or vats 15 passing over the first series of rollers, therein shown, taking up a certain amount of dye. It then passes between squeeze rollers 15^a from which it is 100 conducted off over rollers 16 a distance in order to give it proper exposure to the air to oxidize the dye, it is then again dipped into the vat dye liquid passing over rollers 15^b, thence between squeeze rollers 15^c, from 105 which it is conducted off over rollers 17, 18, 19, a distance to again give it proper exposure to the air, to again oxidize the dye and, continuing, the warp is conducted 110 through the washing machine 20—21, thence over drier rolls 22—23, thence to coilers 24 in perfect condition to be delivered to the beamer, thus the white long chain warp is treated, dyed, dried, coiled, and ready for 115 the beamer without manual handling in one continuous process, and the fibres after being all laid in one direction are not disturbed in this relation throughout the entire process, consequently they are in the same relation when the warp is ready for the beamer that they were when the process started. 120

If preferred a series of dye vats may be used in our continuous process, but in such case they should be in free communication 125 with each other and all of the dye stuff fed into one vat and a pump in that vat keeps the dyeing liquor circulating through the successive vats. This will maintain the same strength of dye in all of the vats. We 130

prefer, however, to use a single dye vat as it is much simpler. But irrespective of the machine, or apparatus, our invention resides in the continuous process of starting with 5 the long chain warp white at the beginning and ending up with it dyed and dry at the other end after one continuous run.

In a mill using dyed long chain warps, that is warps in the long chain or rope form, 10 these warps must be dyed, dried and delivered to the beaming department to be wound on section beams for the next operation. The operations involved in dyeing and drying are long and tedious and the 15 more numerous they are the worse is the condition of the warps when delivered to the beamer. Moreover when warps are run in one direction through an apparatus the small fibres on the outside of the yarn are 20 laid in one direction. When the warp is reversed and run in the opposite direction these fibres are raised from their first position and laid in the other direction, the result being that the various single threads 25 of the warp become matted together. The more processes through which the warp is run separately the worse it runs in the beaming. The ideal condition would be to run them once only and have them ready for 30 beaming. Prior to our invention this has never been accomplished, but we have been delivering to our beamers upward of 72 warps per day which have been entirely finished, boiled out, dyed, oxidized, washed, 35 softened and dried in one single run. The result has been a low cost of production and an improved product.

What we claim is:

1. The continuous method of treating 40 warp in rope form which consists in preparing it and passing it between squeeze rollers, passing it over a set of rollers in a vat dye liquid, conducting it between squeeze rollers then conducting it off to a distance 45 to give proper exposure to air, then conducting it again into the same dye liquid over another series of rollers, then passing it between a pair of squeeze rollers and again conducting it off to a distance to give 50 proper exposure to air, conducting it through a washing machine, thence through a dryer and thence to a coiler.

2. The continuous method of treating 55 warp in rope or chain form which consists in cleaning it and passing it between squeeze rollers, passing it over a set of rollers in a vat dye liquid, conducting it between squeeze rollers then conducting it off to a distance to give proper exposure to air, then 60 conducting it again into the same dye liquid over another series of rollers, then passing it between a pair of squeeze rollers and again conducting it off to a distance to give proper exposure to air, conducting it 65 through a washing machine, thence conduct-

ing it through a pair of squeeze rollers and then through a dryer, and thence to a coiler.

3. The continuous method of treating warp in rope or chain form which consists in cleaning it and passing it between squeeze rollers, 70 passing it over a set of rollers in a vat dye liquid, conducting it between squeeze rollers, then conducting it off to a distance to give proper exposure to air, then conducting it again into the same dye liquid over another 75 series of rollers, then passing it between a pair of squeeze rollers and again conducting it off to a distance to give proper exposure to air, conducting it through a washing machine, then conducting the warp through 80 two washing vats, thence through a pair of squeeze rollers and through a dryer to a coiler.

4. The continuous method of treating warp in rope or chain form which consists 85 in cleaning it and passing it between squeeze rollers, passing it over a set of rollers in a vat dye liquid, conducting it between squeeze rollers, then conducting it off to a distance to give proper exposure to air, then conducting it again into the same dye vat over another series of rollers, then passing it between a pair of squeeze rollers and again conducting it off to a distance to give proper 90 exposure to air, conducting it through a washing machine, then through a pair of squeeze rollers, and thence through a dryer 95 and to coilers.

5. The continuous process of treating 100 warp in rope or chain form which consists in laying the fibres all in the same direction, boiling out the warp, dipping the warp in vat dye, oxidizing the warp, re-dipping in the same dye, again oxidizing the warp, washing it and drying the warp.

6. The continuous process of treating 105 warp in rope or chain form which consists in boiling out the warp, dipping the warp in a vat dye, oxidizing it, re-dipping it in the same dye, again oxidizing it, washing it and drying it.

7. The continuous process of treating 110 warp in rope or chain form which consists in boiling out the warp, dipping the warp in vat dye, oxidizing it, re-dipping it in the same dye, again oxidizing it, washing it and drying it, and delivering it to a coiler.

8. The continuous process of treating 115 warp in rope or chain form which consists in boiling out the warp, dipping the warp in a vat dye, oxidizing the warp, and re-dipping it in the same dye, again oxidizing the warp and washing it, and drying the warp, and agitating the dye in the vat.

9. The continuous process of treating 120 warp in rope or chain form which consists in boiling out the warp, dipping the warp in a vat dye, oxidizing it, re-dipping it in the same dye, again oxidizing it, and repeating the dipping and oxidizing steps any 125 130

number of successive times required to obtain the required shade, washing it and drying it.

10. The continuous method of treating 5 long warp in rope or chain form which consists in preparing the warp to absorb the dye, passing it through a vat dye liquid, passing it through squeeze rollers and conducting it off to a distance in order to give 10 proper exposure to the air, then conducting it again into the dye liquid, thence through squeeze rollers and again conducting it off to a distance in order to give proper 15 exposure to the air, and repeating this dipping in the dye and exposure to air steps any number of successive times with the exposure to the air between the dips into the dye liquid to obtain the required shade, and then conducting the warp through a 20 dryer and thence to a coiler, whereby white warp at the beginning of the process after one continuous run is delivered to the coiler dyed and dry.

11. The continuous process of treating 25 warp in rope or chain form which consists in boiling out the warp, cooling it, dipping it in a vat dye liquid and oxidizing it, and repeating the dipping and oxidizing steps any number of successive times with exposure to the air between the dips into the 30 dye liquid to obtain the required shade and then washing and drying the warp and thence delivering it to a coiler.

12. The continuous process of treating 35 warp in a chain or rope form which consists in wetting the warp, dipping it in a vat dye liquid and oxidizing, and repeating the dipping and oxidizing steps to obtain the required shade, maintaining the dye at 40 standard strength, and then washing and drying the warp and thence delivering it to a coiler.

13. The continuous method of treating warp in chain or rope form which consists in passing it through preparing vats which 45 contain liquid to wet and prepare the warp to absorb the dye, and passing it through squeeze rollers, thence passing under a set of rollers in the vat dyeing liquid, conducting it between squeeze rollers, thence conducting it to a distance to give proper exposure to air for oxidizing, then conducting it again in to the same dye vat under another series of rollers, then conducting it off to a distance to give proper exposure to air for oxidizing and repeating this dipping into the dye liquid any number of successive times with proper exposure to air between the dips into the dye liquid to obtain the required shade, then conducting the warp through a washing vat and thence conducting it through a dryer and thence to a coiler.

14. The continuous process of treating warp in rope or chain form which consists 65 in dipping it in a vat dye liquid and oxidizing it, and repeating the dipping and oxidizing steps the necessary successive times to obtain the required shade, maintaining the dye at a standard strength, then washing 70 and drying the warp and delivering it to a coiler.

15. The continuous process of treating warp in rope or chain form which consists in dipping it in a vat dye liquid and oxidizing it, and repeating the dipping and oxidizing steps the necessary successive times to obtain the required shade, maintaining the vat dye at a standard strength, drying 75 the warp and delivering it to a coiler.

In testimony whereof we affix our signatures.

HAROLD MASON CHASE.
GEORGE WILMOT ROBERTSON.
